(57) **CLAIM**

The ornamental design for a prosthesis liner, as shown and described.

DESCRIPTION

FIG. 1 is a front elevation of a prosthesis liner showing my new design, the side opposite being a mirror image;

FIG. 2 is a top plan view thereof;

FIG. 3 is a bottom plan view thereof;

FIG. 4 is a front elevation of a modified embodiment of the design shown in FIGS. 1 through 3, the side opposite being a mirror image;

FIG. 5 is a top plan view thereof;

FIG. 6 is a bottom plan view thereof;

FIG. 7 is front elevation of a second modified embodiment of the design shown in FIGS. 1 through 3, the side opposite being a mirror image;

FIG. 8 is a bottom plan view thereof; and,

FIG. 9 is a top plan view thereof.

The broken lines showing the interior of the design in FIGS. 2, 5 and 8 are for illustrative purposes only and form no part of the claimed design.
